UNITED STATES PATENT OFFICE.

LEWIS PETERSON, OF SAN RAFAEL, ASSIGNOR TO THE WESTERN CLOCK ADVERTISING COMPANY, OF SAN FRANCISCO, CALIFORNIA.

ADVERTISING-CLOCK.

SPECIFICATION forming part of Letters Patent No. 499,931, dated June 20, 1893.

Application filed August 19, 1892. Serial No. 443,511. (No model.)

To all whom it may concern:

Be it known that I, LEWIS PETERSON, a citizen of the United States, residing at San Rafael, Marin county, State of California, have 5 invented an Improvement in Advertising-Clocks; and I hereby declare the following to be a full, clear, and exact description of the same.

My invention relates to that class of advertising devices in which a series of advertising placards is periodically driven to exhibit successive placards, by means of a clock operating through suitable intermediate mechanisms.

15 My invention consists in the novel combination and arrangement of parts hereinafter fully described and specifically pointed out in the claims.

The object of my invention is to provide a 20 simple, effective and attractive device of this class.

Referring to the accompanying drawings for a more complete explanation of my invention,—Figure 1 is a front elevation, a portion 25 of the face of the casing being broken away. Fig. 2 is a side elevation, part of the casing being broken away. Fig. 3 is a detail of the end of lever H.

A is a casing of suitable ornamental character. In its lower front it has a sight aperture a, the top of which has a hood a' which serves as a guide for the successive advertising placards B as they approach their point of dropping to exhibit their faces. The 35 placards are pivotally mounted in the circumference of revoluble end disks C, carried by a shaft D, which is mounted in suitable standards d.

In the top of casing A is a clock E having 40 the usual dial and hands.

The mechanism of the clock is of the ordinary description and is designated generally by e.

In the lower portion of the clock frame is a 45 shaft F which carries a pinion f. This pinion engages the gearing of the clock mechanism as shown, whereby it and the shaft F derive a rotary motion. Shaft F also carries a cam wheel G consisting of a disk with a cir-

cumferential series of inclined drop planes or 50 cams g.

H is a pivoted lever, one extremity of which bears on the cams of wheel G, an anti-friction roller h preferably intervening. To the other extremity of lever H is connected an 55 actuating pawl I which engages with a ratchet J on the shaft D below. A retaining pawl K controls this ratchet.

L is a gong, and M is a striker carried by the lever H and adapted to hit the gong. 60

The operation is as follows:—The shaft F being rotated by the clock mechanism, the cams of wheel G bear down successively upon the lever H and successively relieve it. Bearing down upon this end of lever H raises its 65 other end, and this movement lifts pawl I, which, through its engagement with ratchet J turns shaft D and the end disks C. A placard B is thus brought forward past the guide hood a' and it then drops by gravity thus exposing its face. Then the cam, relieving the lever H, said lever drops its lower extremity and lowers the pawl I for engagement with the next tooth of the ratchet J, and this same dropping of lever H causes the striker to hit 70 the gong and thereby attract attention to the exhibition of the placard. The operation being repeated, the several placards are successively exhibited. The time during which each placard is exhibited can be properly determined by the movement given to the cam wheel G. 75

Having thus described my invention, what I claim as new, and desire to secure by Letters Patent, is—

1. The combination of the shaft D having the disks C with the series of pivotally mounted swinging and successively dropping placards, the clock mechanism, the shaft F driven thereby and having a cam wheel G, the pivoted lever having one extremity impinging on said cam wheel, the pawl I attached to its other extremity and the ratchet J on shaft D, with which said pawl engages, substantially as herein described. 85

2. The combination of the shaft D having the disks C with the series of pivotally mounted swinging and successively dropping pla- 90

95

cards, the clock mechanism, the shaft F driven thereby and having a cam wheel G, the pivoted lever having one extremity impinging on said cam wheel, the pawl I attached to its 5 other extremity, the ratchet J on shaft D with which said pawl engages, the striker carried by the pivoted lever and the gong with which said striker comes in contact by the move-

ment of the lever, substantially as herein described.

In witness whereof I have hereunto set my hand.

LEWIS PETERSON.
